US0D1046678S

(12) **United States Design Patent** (10) **Patent No.:** **US D1,046,678 S**
(45) **Date of Patent:** **** Oct. 15, 2024**

(54) **EARRING**

(71) Applicant: **Venus by Maria Tash, Inc.**, New York, NY (US)

(72) Inventor: **Maria Tashjian**, New York, NY (US)

(73) Assignee: **Venus by Maria Tash, Inc.**, New York, NY (US)

(**) Term: **15 Years**

(21) Appl. No.: **29/841,914**

(22) Filed: **Jun. 9, 2022**

Related U.S. Application Data

(63) Continuation of application No. 29/769,373, filed on Feb. 4, 2021, now Pat. No. Des. 954,591, which is a continuation of application No. 29/725,811, filed on Feb. 27, 2020, now Pat. No. Des. 983,076.

(51) **LOC (14) Cl.** 11-01

(74) *Attorney, Agent, or Firm* — Dentons US LLP

(57) **CLAIM**

The ornamental design for an earring, as shown and described.

DESCRIPTION

FIG. 1 is a perspective view of a first embodiment of an earring;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof.

FIG. 8 is a perspective view of a second embodiment of the earring;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

Broken lines shown in drawings illustrate portions of the earring that form no part of claimed design.

1 Claim, 14 Drawing Sheets

US D1,046,678 S
